LOCK MECHANISM

Filed June 23, 1926

UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION, OF MICHIGAN.

LOCK MECHANISM.

Application filed June 23, 1926. Serial No. 117,941.

This invention relates to lock mechanism and particularly to means for locking and unlocking the ignition switch of a motor vehicle.

5 One of the objects of the invention is to provide an ignition switch with both key and keyless release mechanism of novel and efficient form.

Another object of the invention is to provide the ordinary type of ignition switch 10 with means mounted adjacent thereto for retaining it in locked position and for releasing the locking means either by key or keyless means.

15 Another object of the invention is to provide a dial operated release means with a combination release lever and click mechanism.

Other objects of the invention will appear 20 from the following description taken in connection with the drawings, which form a part of this specification, and in which:

Fig. 1 is an elevation view of a motor vehicle switch mechanism embodying the invention;

Fig. 2 is a vertical sectional view substantially on the line 2—2 of Fig. 1;

Fig. 3 is a vertical section substantially on the line 3—3 of Fig. 2;

30 Fig. 4 is a section on the line 4—4 of Fig. 2;

Fig. 5 is a section on the line 5—5 of Fig. 2, and

Fig. 6 is a view in partial horizontal section on line 6—6 of Fig. 3.

Referring to the drawings, 10 represents the casing of a switch mechanism such as is mounted on the instrument board of a motor vehicle. It is usually formed of two principal parts, the part 11 forming the front and sides of the casing and the part 12 forming a detachable rear cover plate. The mechanisms hereinafter described are supported on or in said casing. Two switch handles 13 and 14 are shown in Fig. 1, and usually the switch handle 13 is connected to the ignition switch and the handle 14 to the lighting switch. The latter is shown only in Fig. 1.

In Fig. 3 the switch 15 to which the handle 13 is connected is shown as having a shaft portion 16, and an arm 17 to which is connected a spring 18 having its other end connected at 19 to the casing so that the switch is yieldingly retained in one of its positions. The switch also has a segmental arm 20 upon

which is an insulated contact plate, shown in dotted lines at 21, which contact plate cooperates with contact points 22 and 23 (the latter shown in dotted lines) for making and breaking the ignition circuit. In Fig. 3 the switch is shown in its "off" position. In this position it is retained by a locking member or bolt 24 which is supported to slide in the casing as in the guides 25. The bolt 24 catches behind a notch or shoulder 26 in the switch and retains the switch in "off" position until the bolt is withdrawn. The switch is then released and is moved by the spring 18 to its "on" position in which the contact piece 21 connects the contacts 22 and 23. 70

There are two release mechanisms for withdrawing the bolt 24 and releasing the switch. One of these comprises a two-piece shaft 27 mounted in the casing and secured together through splines 28 and a bolt 29 threaded to the inner member of the shaft, as at 30. The knurled head 31 of the bolt permits the bolt to be unscrewed and the two parts of the shaft 27 to be adjusted angularly for the purpose hereinafter described. A 80 stop screw 32 at the inner end of the bolt 29 prevents complete withdrawal of the bolt as long as said screw is in place.

The shaft 27 has a cam 33 arranged near its inner end, which cam corresponds to one 85 of the numerals on a dial or disk 34 at the outer end of the shaft. A release lever 35 mounted in the casing with its head in the slot 36 of the locking bolt 24, is arranged to be rocked on its pivot 37 by the cam 33 90 when the shaft 27 is pushed inwardly. The cam, however, will not operate the lever 35 unless it is first moved to a position in line with the lever, and this may be done by operating the shaft 27 through the dial 34. By 95 thus rotating the shaft and moving it endwise with the cam 33 and lever 35 in line, the latter is rocked on its pivot 37 and the bolt 24 is withdrawn against its spring 38 and the switch 15 is released. However, if 100 the shaft 27 is pushed inwardly in any other position of the cam 33, the lever 35 will fall behind a shoulder 39 on the shaft and retain the shaft against retraction. Also, as the shaft is pushed inwardly a stationary lug 105 40, shown in Fig. 3 and Fig. 6, immediately enters in one of the longitudinal slots 41 on said shaft and prevents rotation of the shaft. Thus the shaft can be neither rotated nor moved endwise if it is caught 110

by the lever 35 behind the shoulder 39 and the dial release mechanism is thereby retained ineffective by reason of this wrongful manipulation of the dial mechanism.

5. If the dial mechanism is correctly operated to release the locking bolt 24, a spring 42 returns it endwise to its original position and another spring 43 rotates it to its original angular position which is preferably at zero 10 indication on the dial. Said spring 43 has one end fixed to the casing, as at 44, and its other end 45 is held in a ring 46 keyed to the shaft 27. The ring has a stop pin 46' thereon which co-operates with a lug 44' 15 on the plate 44" on the casing to stop the shaft at its zero position on the dial.

In order that the dial mechanism may be operated at night as well as in the daytime, the lever 35 operates in conjunction with the 20 splines or slots 41 as a click mechanism, a spring 47 operating to yieldingly press the lever 35 towards the shaft. For this purpose, and for the purpose of permitting the lever 35 to drop behind the shoulder 39 there is 25 slight lost motion or play between the lever 35 and the ends of the slot 36.

From the above it will be seen that the dial mechanism may be operated to release the bolt 24 by rotating the shaft 27 to correct 30 position with the cam 33 in line with the nose of the lever 35 and then pushing the shaft inwardly so that the lever rides on the cam and withdraws the bolt. The springs 42 and 43 will then automatically return the shaft 35 to its original or normal position.

Should the owner or operator of the vehicle believe that some unauthorized person has learned the combination number, he may easily change it by unscrewing the bolt 29, 40 pushing the inner part of the shaft 27 inwardly relative to the outer part, turning the two parts relative to each other several numbers on the dial, and then screwing up the bolt 29 to lock the two parts of the shaft 45 together. This changes the relationship of the cam 33 to the dial and consequently another dial numeral will correspond to the cam position.

After the dial mechanism has been incorrectly operated so that it is locked by the 50 lever 35 and the lug 40, (see Fig. 6) it can only be reset by movement of the locking bolt 24. This may be done by a key mechanism as illustrated in the drawing. The key 55 mechanism is generally indicated at 48 and comprises the usual lock cylinder 49 and a pin 50 which may be moved by the lock cylinder against a lug 51 on the bolt 24 to thereby withdraw the bolt and release the 60 ignition switch. This movement of the locking bolt 24 will withdraw the lever 35 from behind the shoulder 39 and the springs 42 and 43 will then return the dial mechanism to its original or normal position.

65 While I have herein described in some de-

tail a specific embodiment of my invention, which I deem to be new and advantageous and may specifically claim, I do not desire it to be understood that my invention is limited to the exact details of the construction, 70 as it will be apparent that changes may be made therein without departing from the spirit or scope of my invention.

Having thus described my invention, what I claim and desire to secure by Letters Pat- 75 ent is:

1. In a switch locking mechanism, the combination of a support, a switch mounted on the support, a locking member mounted on the support and adapted to retain the switch 80 in one of its positions, a rotatable and endwise movable element having a device thereon to move said element to thereby release said switch from said position, and means for rendering said element inoperative after 85 it has been moved endwise with said device in any other than said predetermined position.

2. In a switch locking mechanism, the combination of a spring actuated switch, a locking member adapted to retain said switch in 90 "off" position, a key mechanism and a keyless mechanism for moving said locking member to release the switch, said mechanisms and said member being mounted adjacent but independently of the switch, and means for 95 rendering the keyless mechanism inoperative upon wrongful manipulation thereof in the first instance.

3. In an ignition mechanism for motor vehicles, the combination of an ignition switch 100 spring operated to "on" position, a locking member adapted to catch and hold the switch in "off" position, a cam and dial mechanism for moving said member to release the switch, said mechanism having means to make it inoperative upon wrongful manipulation in the first instance, and key actuated mechanism 105 for moving said member and resetting the dial mechanism.

4. In a switch locking mechanism, the combination of a switch, a locking bolt therefor, key operated mechanism for withdrawing said bolt, dial mechanism for withdrawing the bolt, and means whereby the key mechanism will reset the dial mechanism. 110

5. In a switch locking mechanism, the combination of a casing, a switch supported therein, a locking bolt supported in the casing and co-operating with said switch, key operated release means for said locking bolt, dial operated release means for said locking bolt, means for rendering ineffective said dial operating means upon the wrongful manipulation thereof, said key operated release means being operative to reset the dial operated means when the latter has been rendered ineffective. 120

6. In a switch locking mechanism, the combination of a casing, a switch mounted therein and having a spring to yieldingly retain it in 125

- one position, a locking bolt co-operating to retain said switch in its other position, a key operated device adapted to release said locking bolt, a lever connected to move said bolt 5 to release position, a shaft having a cam thereon adapted to rock said lever, a dial on said shaft, means on said shaft co-operating with said lever to form a click mechanism, and means for preventing rotation of the dial 10 except when the shaft is in its retracted or idle position.
7. In a lock, a rotatable member to be locked, a spring adapted to cause rotation of said member, a locking element adapted to 15 retain said member against rotation and means comprising a rotatable and transversely movable member, adapted to actuate said locking element, whereby said member is rotated under the action of said spring.
20. 8. In a lock, a rotatable member, a dog on said member, a slotted shaft having one end adapted to engage said dog, a lever inserted in said slot to actuate said shaft, and a cam- shaft capable of transverse and rotary motion, a cam on said shaft engaging one end of 25 said lever.
9. In a lock, a rotatable member, means normally tending to cause rotation of said member, means retaining said member against rotation, and a rotatable and transversely movable member for releasing said retaining means.
10. In a lock, a keyless mechanism for actuating the lock rendered inoperative upon the wrongful manipulation thereof in the first 35 instance and a key mechanism for actuating the lock and resetting the keyless mechanism.
11. In a lock, a keyless mechanism for actuating the lock rendered inoperative upon the wrongful manipulation thereof in the first 40 instance and another mechanism for actuating the lock and resetting the keyless mechanism.

In testimony whereof I affix my signature.
MILTON TIBBETTS.
